[57] **CLAIM**

The ornamental design of a pickup unit for animal droppings, substantially as shown and described.

DESCRIPTION

FIG. 1 is a left side elevational view of a pickup unit for animal droppings showing my new design, the right side being a mirror image of the left side shown;

FIG. 2 is a front elevational view thereof;

FIG. 3 is a top plan view thereof, the bottom being a mirror image of the top shown;

FIG. 4 is a perspective view taken from the top, front and left side thereof.

FIG. 1

FIG. 2

FIG. 3

FIG. 4
